UNITED STATES PATENT OFFICE.

JOHN THOMAS SPRADLING, OF WHITE PLAINS, NEW YORK.

READING-GLASS HOLDER.

1,345,272.

Specification of Letters Patent. Patented June 29, 1920.

Application filed June 19, 1919. Serial No. 305,231.

To all whom it may concern:

Be it known that I, JOHN T. SPRADLING, a citizen of the United States, and a resident of White Plains, in the county of West-
5 chester and State of New York, have invented a new and Improved Reading-Glass Holder, of which the following is a full, clear, and exact description.

This invention relates to new and useful 10 improvements in holders for magnifying glasses, and pertains more particularly to means for supporting a reading glass.

The primary object of the invention is to provide a reading glass holder for use in 15 connection with type-setting machines for the purpose of more clearly bringing out the manuscript of the copy from which the operator is working.

A further object of the invention is to construct a device of this character in such a 20 manner that the reading glass is movable with respect to the manuscript copy.

A still further object of the invention is to construct a device of this character so that 25 the reading glass is automatically returned to its starting point.

With the above and other objects in view, reference is had to the accompanying drawings, in which—

30 Figure 1 is a segmental elevation of a portion of a type-setting machine showing the location of the device with respect to the copy holder and keyboard thereof;

Fig. 2 is a sectional view on the line 2—2
35 of Fig. 1;

Fig. 3 is a detail top plan view.

Referring more particularly to the drawings, the reference character 5 designates the keyboard of a machine and supported 40 from said keyboard in any desired manner; as by means of brackets 6, is the copy board 7.

Extending upwardly from the rear edge of the copy board 7, are two brackets 8, said 45 brackets being secured in place by means of rivets or the like 9. The upper end of each of said brackets 8 is bent outwardly as at 10, and said brackets are each secured as at 11, to a transversely-extending rod or track 12. One end of this track 12 is bent downwardly 50 as at 13, and mounted in the free end of the downwardly-extending portion 13, is a spring drum 14, said drum being freely rotatable on the screw 15, which secures it to 55 the end of the track.

The reference character 16 designates a

reading glass, which is supported over the keyboard 7 by means of a bracket 17, said bracket being in turn secured by means of bolts or the like 19, to a traveling carriage 60 18, which latter is adapted for movement along the track 12. The carriage 18 has each of its free ends bent backwardly upon the body portion 21, as designated by the reference character 20, the said free ends being 65 arranged in spaced relation to each other to permit of movement of the carriage along the track 12. Mounted between each of the free ends 20 and the body portion 21 of said carriage 18, are rollers 22, and, as shown in 70 Fig. 2, said rollers are adapted to engage the opposite side faces of the track 12. As shown in Fig. 2, these rollers are angularly disposed with relation to each other, which angular disposition causes a binding action 75 on the track 12, thus preventing the carriage from rocking under the weight of the reading glass 16, to a position where it would be in operative relation to said track.

Extending around the spring drum 14, is 80 a suitable flexible cord 24, the free end of said flexible cord being attached, as at 25, to said carriage 18, for a purpose to be herein-after described.

Depending from the track 12 on the opposite end to that on which the spring drum 14 is mounted, is an arm 26, and mounted in the opposite end of said arm 26, are rollers 27 and 28.

The reference character 29 designates a 90 bearing block which is secured by means of screws 30, to any suitable part of the machine, and pivotally mounted in said bearing block 29, by means of a pin 31, is a lever 32, said lever being provided on its 95 free end with an operating handle 33. Secured as at 34, to the traveling carriage 18, is a flexible cord 35, said cord passing around the rollers 27 and 28, and having its free end secured, as at 36, to the operating 100 lever 32.

The operation of the device is as follows: The operating lever 32 is so positioned that it is capable of being moved by the knee of the operator as he sits at the machine, 105 and it will be apparent that as said operating lever 32 is moved about its pivot, the reading glass 16 is moved from left to right in Fig. 1, over the manuscript 40, which is positioned on the copy-holder 110 board 7. As the reading glass is moved to the extreme right position, pressure on

the lever 32 is released, at which time under the influence of the spring drum 14 and the flexible cord 24, the reading glass 16 is returned to its normal position at the left-hand side of Fig. 1, the operating lever 32 returning to its normal position under the influence of the flexible cord 35. The reference character 41 designates a stop which is secured to the track 12 and limits the movement of the traveling carriage 18 in a direction to the left in Fig. 1.

I claim:

1. A reading glass holder comprising a pair of spaced brackets, a track having one of its ends downwardly bent and supported by said brackets, a carriage substantially U-shaped in cross section adapted to receive said track between its extended members, rollers mounted in said carriage and adapted to engage opposite sides of the track in different planes, a reading glass carried by said carriage, a spring drum

mounted on the downwardly bent end of said track, means for connecting the spring drum with the carriage, and means for moving the carriage against the action of the spring drum, substantially as described. 25

2. A reading glass holder comprising a plurality of supports arranged in spaced relation, a track carried by said supports and having one of its ends angularly disposed with relation to its main body portion, a carriage, rollers carried by the carriage and adapted to engage the opposite sides of said track to support the carriage thereon, a spring drum carried by the angularly disposed portion of said track and adapted to move the carriage in one direction, means for moving the carriage in the opposite direction, and means carried by the track to limit the movement of the carriage under the influence of the spring motor. 30 35 40

JOHN THOMAS SPRADLING.
